HIS ATTORNEY.

Patented Sept. 7, 1926.

UNITED STATES PATENT OFFICE.

EARL B. LEAR, OF PHILLIPSBURG, NEW JERSEY, ASSIGNOR TO INGERSOLL-RAND COMPANY, OF JERSEY CITY, NEW JERSEY, A CORPORATION OF NEW JERSEY.

DOUBLE-DRUM HOIST.

Application filed March 19, 1926. Serial No. 95,942.

This invention relates to hoists, but more particularly to hoists of the double drum type in which a common driving element may be selectively connected to drive either 5 of the drums.

The objects of the invention are to insure a quick and positive connection between the driving element and either of the drums, and to insure full contact between the pawl 10 and the cooperative engaging members carried by the drums.

Other objects will be in part obvious and in part pointed out hereinafter.

The invention consists of the combination 15 of elements and arrangement of parts substantially as described hereinafter and more specifically pointed out in the appended claims and illustrated in the accompanying drawings, in which—

20 Figure 1 is an elevation, partly in section, of a double drum hoist.

Figure 2 is a transverse view taken through Figure 1 on the line 2—2 looking in the direction of the arrows, and

25 Figure 3 is a plan view, partly in section, taken through Figure 1 on the line 3—3 looking in the direction of the arrows.

Referring to the drawings, the hoist designated generally by A comprises a base plate B on opposite ends of which are mounted end frames C and D. The end frames C and D are preferably formed as separate pieces and secured to the base plate in any suitable and convenient manner. In the present instance a motor E is supported by the end frame C and is intended to be connected to rotate a driving shaft F extending longitudinally of the hoist and supported at its 35 opposite end by the frame D. The motor E may be of any suitable reversible type, in the present instance, a pressure fluid motor is indicated. Accordingly, a valve chest G is provided for the motor E to receive a pressure fluid controlling valve H provided with a suitable throttle lever J whereby said valve may be actuated.

50 Encircling the driving shaft F is a center bearing K supported at its ends by the end frames C and D. The center bearing is preferably secured to the end frames by suitable screws L, thus imparting rigidity to the said end frames and also forming a support for a haulage drum O and a tail

rope drum P upon which are wound the 55 ends of a haulage rope or cable Q.

In the present instance a bushing R encircles the center bearing K to form a bearing at one end of the haulage drum O. The other end of the bushing R serves as a 60 bearing for a sleeve S carrying at one end an internal gear T and at its opposite end a main driver U secured to the sleeve S as by means of keys V.

Suitable means are provided for operatively connecting the driving shaft F with the internal gear T for rotating the main driver U. To that end a pinion W is keyed to one end of the driving shaft F and meshes with an intermediate gear X freely rotatable 70 on a shaft Y. The shaft Y is preferably supported at one end by the end frame D and at its other end in a cover Z secured to the side of a gear casing b, which may be formed integrally with the end frame D. 75

A pinion c preferably formed integrally with the intermediate gear X, as shown, meshes with the internal gear T and is recessed to receive a frictionless bearing d mounted on the shaft Y. 80

In accordance with the present invention, the main driver U is provided with an arm or extension e extending between the drums O and P and has formed near its outer extremity a slot f in which is arranged an 85 oscillatory pawl g. The pawl g is preferably provided with flat top and bottom faces to cooperate slidably with the adjacent faces of the slots f and carries on its side faces teeth h and j. The slot f is formed transversely in a plane offset from and parallel to the axis of the driving shaft so that the pawl g may oscillate through a plane parallel to the axis of rotation of the main driver U. In the present instance the pawl g is pivoted near one end on a pin k having a threaded portion o which cooperates with suitable threads formed in the outer end of the extension e. 95

As illustrated, the engaging surfaces p of 100 the teeth h and j are preferably tapered or "backed off" to insure positive and full engagement with cooperating teeth q and r preferably formed integrally with the drums O and P respectively. The cooperating faces of the teeth q and r are also tapered to correspond to the tapers of the teeth h and j formed on the pawl. 105

Any suitable means may be provided for checking rotation of the drums during the operation of the hoist or for preventing rotation thereof after the drums are disconnected from the driving element. In the present instance, brake bands *t* are arranged to encircle flanges *u* carried by the drums *O* and *P* and are operatively connected to shafts *v* provided with suitable levers *w* whereby the brake bands *t* may be manipulated. However, since the braking element forms no part of the present invention and inasmuch as its operation and functioning is well understood, further description thereof is considered unnecessary.

In the operation of the hoist let it be assumed that it is intended to rotate the tail rope drum *P* for winding up the cable *Q*. The valve *H* may then be actuated to the position for actuating the motor in the required direction, in this instance, in a clockwise direction. The main driver *U* will then, due to the train of gearing which connects it with the driving shaft *F*, be caused to rotate in a counter-clockwise direction, thus causing the pawl *f* to engage one of the teeth carried by the drum *P*, and the drum *P* will then remain interlocked with the main driver until the motor is again reversed. Upon reversal of the throttle valve *H*, and consequently of the motor *E*, the main driver will be caused to rotate in the opposite direction for rotating the haulage drum *O*. Reversal of the main driver will cause the pawl *f* to be forced out of engagement with the tail rope drum by the

teeth *r* and to be simultaneously connected with the teeth *q* carried by the haulage drum *O*.

I claim:

1. In a hoist, the combination of a reversible motor, a driving shaft connected to be rotated by the motor, a pair of drums rotatable about the driving shaft, a main driver connected to be rotated about the driving shaft, a pawl carried by the main driver to connect one or the other of the drums with the said main driver, and means carried by the main driver extending transversely of the axis of the driving shaft for pivoting the pawl to the main driver, the pawl oscillating in a plane offset from and parallel to the axis of rotation.

2. In a hoist, the combination of a reversible motor, a driving shaft connected to be rotated by the motor, a pair of drums rotatable about the driving shaft, a main driver between the drums and connected to be rotated by the driving shaft, a slot in the main driver, an oscillatory pawl in the slot to connect one or the other of the drums with the main driver, and a pin screwed into the main driver to extend through one end of the pawl to form a pivot therefor, said pin extending transversely to the axis of the driving shaft, the pawl oscillating in a plane offset from and parallel to the axis of rotation.

In testimony whereof I have signed this specification.

EARL B. LEAR,
